United States Patent Office.

PHILO B. GILBERT, OF NEW YORK, N. Y.

Design No. 2,646, dated May 7, 1867.

DESIGN FOR A SPOON, KNIFE, OR FORK-HANDLE.

The Schedule referred to in these Letters Patent and making part of the same.

TO ALL WHOM IT MAY CONCERN:

Be it known that I, PHILO B. GILBERT, of the city, county, and State of New York, have invented or produced a new and original Design for Spoons, Forks, Knives, &c., or for the ornamentation of the handles thereof; and I do hereby declare the following to be a full, clear, and exact description of the same, reference being had to the accompanying drawings making a part of this specification, in which—

Figure 1 represents a table-spoon.

Figure 2 represents a dessert or coffee-spoon.

Figure 3 represents a fork.

The top or extreme end of the handle is lozenge-formed, as at *a*, and terminates in scroll and other ornamented work *b*. Next to the above ornamentation follows a medallion, *c*, with a knight's head, *e*, helmeted. Next, an escutcheon, *d*, plain, from which projects the narrow portion of the handle *f*, with sunken marginal and central lines *g*. Next, the spear-shaped points *h*, with a band *i*, and below the band, foliated ornaments *j*, which terminate where the bowl of the spoon, or the spread-out portion of the fork at the head of the tines, begins.

Having thus fully explained my design, what I claim, is—

The above-described ornamentation for handles of spoons, forks, and similar table-ware, as described and represented.

PHILO B. GILBERT.
